ATTORNEY

UNITED STATES PATENT OFFICE.

ROBERT CENTER, OF NEW YORK, N. Y.

CENTER-BOARD WELL FOR VESSELS.

SPECIFICATION forming part of Letters Patent No. 300,570, dated June 17, 1884.

Application filed February 26, 1884. (No model.)

To all whom it may concern:

Be it known that I, ROBERT CENTER, a citizen of the United States, residing in New York city, in the county and State of New 5 York, have invented a new and Improved Center-Board Well for Vessels; and I do hereby declare that the following is a full, clear, and exact description thereof, reference being had to the annexed drawings, forming a part of 10 this specification.

My invention relates to wells formed in vessels for receiving the center-board; and it consists in a well extending from the keel through the deck, having vertical forward and after 15 head-ledges provided with heavy upper trunk-logs, into which the deck-timbers are framed, and furnished with chocks placed between the trunk-logs, with bolts extending through the trunk-logs and chocks to stiffen the vessel 20 and prevent it from working.

It further consists of a hand-tight plank closing the center-board well above the chocks, with the exception of a small aperture through which to reeve the pennant.

25 It further consists in hand-tight pieces inserted in hatch-combings for closing the slot through which the center-board is raised.

Similar letters of reference indicate like parts in the different figures of the drawings.

30 Figure 1 is a side elevation, partly in section. Fig. 2 is a vertical transverse section on line *x* *x* in Fig. 1. Fig. 3 is a transverse section of my improvement applied to an iron vessel. Figs. 4 and 5 show hatch-combings 35 and hand-pieces. Figs. 6 and 7 represent modifications in which the chocks and bolts are placed above the deck.

The lower trunk-logs, A A, rest upon the keel B, and the sides of the trunk C are built 40 upon the lower trunk-logs, A A, in the usual manner. The upper trunk-logs, D D, are heavier than the logs of which the sides of the trunk are formed, and the deck-beams E E, &c., are framed into the upper trunk-logs, 45 D D, and support the deck-plank F in the usual manner. The front and rear head-ledges, 1, 2, extend from the keel to the deck parallel with each other, and a sufficient distance apart to admit of easily raising the center-board out 50 of the well. Chocks G, of a length equal to the width of the center-board well, are placed

at suitable intervals between the upper trunk-logs, D D, and stay-bolts H pass through the upper trunk-logs and through the chocks and bind the trunk-logs firmly against the ends of 55 the chocks. These bolts and chocks, in connection with the heavy upper trunk-logs, are more than sufficient to supply any loss of strength consequent upon cutting the deck-beams. 60

To render the deck continuous over the center-board well, a hand-tight plank, I, is fitted to the top of the well, closing it with the exception of a small aperture through which to reeve the pennant J, which raises and lowers the center-board. The windlass K, by which the center-board is operated, is placed at the end of the center-board well, and the pennant J runs over a sheave, L, journaled in open bearings a, placed on the deck at the sides of the 70 center-board well. Where the center-board well intersects the combing of a hatch or skylight a slot, b, with grooves at either side, is formed in the combing to receive a hand-tight piece, c, fitted thereto, and having the same 75 shape as the combing, as seen in Figs. 4 and 5.

When my improvement is applied to iron vessels, the center-board well is formed of iron plates M, riveted to bars of angle-iron placed at suitable intervals and stayed by plate-knees 80 O, secured to the iron deck-beams N and to the bars of angle-iron. Along the sides of the center-board well and across the ends thereof lodger-plates d are secured to the iron deck-beams to stiffen the framing of the vessel at 85 that point. Sleeves P, of a length equal to the width of the center-board well, are placed between the plates M at suitable intervals, near the top of the well, and bolts Q pass through the plates M and sleeves P, binding the said 90 plates.

When a vessel is designed to carry a cargo that will entirely fill the space beneath the deck, so that it would be impossible to remove the bolts which bind the two sides of the well 95 together when the said bolts are located below the deck, the upper trunk-logs, D D, or the iron plates M M are extended above the deck a sufficient distance to receive the bolts H or Q above the deck. 100

To unship the center-board its pivotal pin is removed, and the hand-tight plank I, also

the bolts and chocks or sleeves, are taken out, and the center-board is attached by suitable tackle to the gaff and raised up through the well, after removing the sheave L from its bearings.

5. The center-board of a vessel to which my improvement has been applied can be unshipped and taken up through the deck to be cleaned or repaired when the vessel is in shoal water, and when the center-board could not be "swept" in the usual way.

Having thus described my invention, what I claim as new, and desire to secure by Letters Patent, is—

15. 1. A center-board well for vessels, extending through both keel and deck, and provided with forward and after head-ledges, and having heavy upper trunk-logs into which the beams are framed, and provided with stay-bolts and chocks or sleeves above and below the deck, as specified.

2. The combination, with a center-board well made as herein described, and extending

through both keel and deck, of a hand-tight piece for closing the well, as specified.

3. The combination, with the center-board well having parallel forward and after head-ledges, as herein described, of a windlass, K, and removable sheave L.

4. The combination, with a center-board well constructed as herein described, and extending through both keel and deck, of a slotted hatch-combing and hand-piece fitting thereto, as herein described.

5. The combination, with a center-board well formed of iron plates M, riveted to vertical stiffening-bars, as described, of the plate-knees O, secured to the vertical stiffening-bars of the well and to the iron deck-beams N, the deck-beams N, and lodger-plates d, as specified.
